Dear Fairbank Wright & Hirsch

UNITED STATES PATENT OFFICE

JACK CARL JANKUS, OF SCRANTON, PENNSYLVANIA, ASSIGNOR TO GAS REFRIGERATION CORPORATION, OF DOVER, DELAWARE, A CORPORATION OF DELAWARE

REFRIGERATOR BOX

Application filed March 17, 1926. Serial No. 95,189.

This invention is an improvement in refrigerators, and relates more particularly to the construction and insulation of the walls and the means for supporting the ice. So far as the wall construction is concerned, the invention is equally applicable to refrigerators of the type in which the cooling is done by a cooling coil, an evaporator, or other means, instead of ice.

10 One object of the present invention is to more effectively seal the insulation so that moisture cannot gain access thereto, as for instance by air currents resulting from temperature changes within the wall. In many 15 respects the wall construction is very similar to that disclosed and claimed in my prior copending application, Serial No. 747,768, filed November 4th, 1924.

A further object of the present invention 20 is to so design and construct the parts within the refrigerator that they may be readily removed for cleaning and, when in place, provide adequate means for permitting and controlling the circulation of air to and from 25 the main provision compartment.

In the preferred form of my improved refrigerator, the ice box is at one side of the main chamber and as an important feature, I provide a partition spaced from the ice receiver to control the air circulation, this partition being so designed and supported that it may be easily removed.

As another important feature, I provide 35 an ice receiver which has side walls to protect the lining of the refrigerator from contact with the ice, and to provide air circulating space, and this receiver is also readily removable.

40 In my improved construction the removal of the inner parts leaves a free and open chamber to which access may be readily gained, and which may be easily and thoroughly cleaned.

45 In the accompanying drawings I have illustrated merely one embodiment of my invention, although it will be evident that other constructions might be designed within the scope of my invention as defined in the 50 appended claims. In these drawings:

Fig. 1 is a front view, the doors being removed.

Fig. 2 is a vertical section on the line 2—2 of Fig. 1, certain of the parts being shown in elevation.

Fig. 3 is a view similar to Fig. 1, but with certain of the parts broken away.

Fig. 4 is a section on the line 4—4 of Fig. 1, certain parts being in elevation.

Fig. 5 is a plan view of the ice receiver removed from the refrigerator.

Fig. 6 is a vertical section on the line 6—6 of Fig. 5.

Fig. 7 is a perspective view of the ice support within the receiver.

Fig. 8 is an enlarged sectional detail on the line 8—8 of Fig. 3.

Fig. 9 is a horizontal section on the line 9—9 of Fig. 1, but on a very much smaller scale.

Fig. 10 is a front view of the refrigerator lining, certain parts being broken away, and the entire lining being shown on the same scale as in Fig. 9, and

Fig. 11 is a detail of one of the shelf supports.

In my improved construction the walls include angle irons 15 which extend along the four edges of the top and bottom, and also extend vertically along the two back corners 80 of the casing. These angle irons may be connected together at their corners to form a skeleton frame, or they may merely connect with each other at the corners, or in some constructions, may be made shorter so that 85 they do not connect. The angle irons may face either outwardly or inwardly, as disclosed in my copending application above referred to, but are illustrated as having their flanges extending outwardly. Between 90 the flanges of each angle iron is mounted a strip 16 which may be of wood or other suitable non-conducting material, these strips being of such dimensions that they project beyond the edges of the flanges. Secured 95 to these angle irons are the outer layers or boards 17 of the walls. The connecting bolts extend through the strips 16 into the angle irons, so that the parts are rigidly connected together, but the outer boards or panels 17 100

are out of direct contact with the metal angle irons.

The lining 18 of the refrigerator is formed of sheet metal with the top, bottom and sides welded or integrally connected so as to form a box with an open front of substantially the size of the front of the entire refrigerator. The sheet metal at the front edges of the top, bottom and side walls, is provided with outwardly extending flanges 19 which are secured to the inner surface of a front door frame 20. This door frame is secured to the angle irons in the same way as are the outer panels 17, and is preferably of wood with openings of the proper size for the doors. The flanges 19 are connected to the door frame 20 by wood screws or other suitable connecting means, and some sealing material, such as for instance as white lead is employed between the two parts so as to form a substantially gas-tight joint. Thus, variation in air pressure in the refrigerator, due to sudden opening or closing of the door, or to any other cause, cannot force air into or draw air out of the space within the walls outside of the lining, and thus moisture from the interior of the refrigerator cannot gain access to the wall packing. The lining is of such dimensions in respect to the refrigerator box, and the angle irons, that the lining is spaced from and entirely out of contact with the angle irons. Thus there is no metal-to-metal heat conduction from the lining to the exterior of the refrigerator. Between the lining 18 and the outer panels or wall layers 17, is the packing 21 which may be of any suitable material. The lining is supported wholly by the door frame 20, and by the packing 21, so that there can be no direct heat conduction to the lining except at the very narrow edges around the doors.

The doors are preferably formed of an outer body section 22 with a sheet metal lining 23 spaced therefrom to receive a layer of insulating packing 24. The marginal flanges 25 of the lining are directly connected to the door about the periphery of the latter, and over these flanges are strips 26 provided with grooves which receive packing strips 27. These packing strips are preferably of rubber tubing, and project beyond the surface of the strips 26 so that when the door is closed they are compressed against the outer surface of the door frame 20.

Within the refrigerator there is mounted a vertical partition 28 which separates the interior into two main chambers, 29 and 30. This partition 28 is preferably formed as a thin sheet metal box, that is, it has opposite walls 31 of sheet metal with intermediate packing 32. The partition terminates a short distance beneath the top of the refrigerator so that air may cross from the provision compartment 30 to the ice compartment 29, and likewise terminates a short distance above the bottom of the

refrigerator so that the cold air passing down over the ice may flow laterally into the lower part of the provision compartment. The partition is supported at its upper end by two pairs of pins 33 which project forwardly from the back wall and rearwardly from a middle strip or mullion 34 of the door frame. These pins are spaced apart to a distance substantially equal to the thickness of the partition so that the partition may be moved vertically between the pins, but cannot be moved laterally to any appreciable extent. Adjacent to the lower part of the refrigerator there are two similar pairs of pins 35 for guiding the lower part of the partition, and between and below these pins 35 are a pair of pins 36 which act as the supports for the weight of the partition. In placing the partition in position, it is moved upwardly between the pins 33 until this lower end is above the pins 35. The lower end is then moved laterally to a position between the pins 35, and the partition is lowered until it rests on the pins 36. Thus the partition when in place is rigidly supported against any lateral or swinging movement, and cannot be moved except by a bodily lifting upwardly from between the pins 35. No tools are required for removing or inserting it, and the retaining members are of very simple and inexpensive design.

The partition, together with one side wall of the refrigerator, serve to support the various shelves which may be employed for the provisions. The shelf supports are in the form of pins 36, one of which is shown in Fig. 11. Each pin is a short metal rod with a reduced threaded end projecting through the lining 18 or the sheet metal 31, as the case may be, and locked in place by a nut on its inner end. When these nuts are tightened and embedded in the insulation at the time the refrigerator is assembled, it will be evident that the shelf supports are rigidly and permanently secured in place.

Within the ice compartment 29 there is provided an ice receiver which may be formed of sheet metal with side walls 38 and a rear wall 39. The ice receiver is open at the front and at the top, and the three sheet metal walls are connected to a metal frame 40 at their lower edges. This frame preferably has a central opening 41 encircled by an upstanding flange 42, and has at its outer edge upstanding flanges 43 to which the walls 38 and 39 are secured. Along one side it may have a front flange 43 which may engage with a transverse member or mullion 44 of the door frame, so as to aid in supporting the ice receiver. The receiver is supported by a pair of metal cleats 45 which are secured to the inner surface of the lining 18 at the back of the refrigerator, and to the cross member 44 of the door frame. The lining at the rear may be reinforced to better support the cleat 45 if desired. As shown, the outer surface

of the lining has a reinforcing strip 46 so that the screws or rivets which hold the cleat 45 in position extend through into this reinforcing strip, rather than merely into the sheet metal of the back. This reinforcing strip may be omitted if desired, in which case washers and nuts of adequate size may be employed on the attaching screws for the cleat 45. Within the ice receiver is an ice support which may be constructed substantially as shown in Fig. 7. This is in the form of a table 47 with depending flanges 48 along its edges, which flanges have recesses or openings 49, for the flow of air. The flanges 48 may rest directly upon the metal frame 40 in the annular channel between the flanges 42 and 43. The cold air from the ice may flow through the openings 49 and thence through the opening 41 while the drip water from the ice will collect in the annular groove or channel outside of the flange 42, and may be drawn off through a drain pipe connected to an opening 50. The ice receiver being open at the front, permits ice to be very easily placed therein, but the side and back walls prevent the lining from being dented or injured by the careless dumping of heavy ice into the receiver. The walls 38 and 39 are spaced from the lining of the refrigerator so that there is a thin air space between. This keeps the ice out of direct contact with the lining, and prevents the direct transmission of heat through the walls to the ice.

In the specific construction illustrated there are three doors, one for the ice compartment, one beneath the ice compartment and one at one side thereof. It will, of course, be evident that the compartment at the side of the ice compartment may be eliminated and only the space beneath the ice compartment employed for storage purposes, or, on the other hand, the compartment beneath the ice compartment might be eliminated. It will also be evident that the main compartment at one side of the ice compartment may have a horizontal cross mullion dividing it in two, so that there would be a door above and one below.

In the construction illustrated the angle irons 15 have their flanges turned outwardly. Obviously, they might be turned inwardly and provided with sealing strips on the outside of the angles as shown in my Patent No. 1,646,616, issued Oct. 25, 1927 on my copending application. The wooden strips 16 serve primarily to form an airtight seal, as the wood panels are forced into contact therewith. In this way a more effective seal is formed than if the panels were in direct contact with the metal of the iron channels.

Having thus described my invention, what I claim as new and desire to secure by Letters Patent is:—

1. A refrigerator casing having a removable vertically disposed partition extending

from the front to the rear thereof, guide pins carried by the lining upon opposite sides of said partition for engaging with the latter and preventing lateral movement thereof, and a supporting member also carried by said casing and upon which said partition rests, said partition being removable from the casing upon the vertical movement of the partition to bring the lower end thereof above the lower guiding pins.

2. A refrigerator casing having a removable vertically disposed partition extending from the front to the rear thereof, a pair of guide pins upon opposite sides of the partition adjacent to the upper end thereof, a similar pair of guide pins upon opposite sides of the partition adjacent to the lower end thereof, and means below and between said last mentioned pins for supporting the weight of the partition.

3. A refrigerator having a removable vertically disposed imperforate partition extending from the front to the rear thereof and spaced from the top, and an ice receiver supported at one side of said partition independently thereof and having an imperforate side wall spaced from and substantially parallel to said partition, said partition on the side thereof opposite to said ice receiver being provided with removable shelf supports.

4. A refrigerator having a removable vertically disposed imperforate partition extending from the front to the rear thereof and spaced from the top of said partition, including a layer of insulating material and having upon one side thereof a series of shelf supports, and an ice receiver at the opposite side of said partition and having a side wall parallel to and spaced from said partition to form an air passage.

Signed at Brooklyn, in the county of Kings and State of New York, this 12th day of March, A. D. 1926.

JACK CARL JANKUS.
